Specification for Design.

Patented Apr. 20, 1920.

Application filed September 30, 1919. Serial No. 327,601. Term of patent 14 years.

To all whom it may concern:

Be it known that I, CHARLES W. MANZEL, a citizen of the United States, residing at Buffalo, in the county of Erie and State of New York, have invented a new, original, and ornamental Design for a Body of an Airship, of which the following is a specification, reference being had to the accompanying drawing, forming part thereof, and in which—

Figure 1 is a top plan view of the body of an airship embodying the design. Fig. 2 is a side elevation thereof, and Fig. 3 an end view.

I claim:

The ornamental design for a body of an airship, as shown.

CHARLES W. MANZEL.
